UNITED STATES PATENT OFFICE.

GEORGE R. GIBSON, OF ELLWOOD CITY, PENNSYLVANIA.

TREAD-PLATE SHAPER.

1,139,266.

Specification of Letters Patent. Patented May 11, 1915.

Application filed June 2, 1914. Serial No. 842,438.

To all whom it may concern:

Be it known that I, GEORGE R. GIBSON, a citizen of the United States, residing at Ellwood City, in the county of Lawrence and State of Pennsylvania, have invented new and useful Improvements in Tread-Plate Shapers, of which the following is a specification.

The invention relates to tread plate shaping machines, and more particularly to the class of machines for shaping tread plates for use in the construction of metallic spiral chutes.

The primary object of the invention is the provision of a machine of this character wherein a tread plate will first be corrugated, and thereafter straightened to increase or stretch the outside edges of the plate, while the medial or center portion thereof remains fixed so as to give the proper twist or shape to the plate when finished.

Another object of the invention is the provision of a machine of this character wherein the corrugated and smoothing rolls may be readily and easily adjusted so as to vary the twist or shape of the plate when passed through the machine.

A further object of the invention is the provision of a machine of this character wherein the corrugated rolls are driven slower with respect to the smoothing rolls so as to insure the proper twisting of the plates when operated upon by the machine; the corrugating of the sheets creates a tension therein to effect the proper twisting thereof.

A further object of the invention is the provision of a machine of this character which is extremely simple in construction, reliable and efficient in its operation, and inexpensive in manufacture.

Other objects will be in part obvious and in part hereinafter pointed out.

The invention accordingly consists in the construction, combination of elements and arrangement of parts which will be exemplified in the construction hereinafter set forth, and the scope of the application of which will be indicated in the appended claims.

In the drawings:—Figure 1 is a front elevation of a machine constructed in accordance with the invention. Fig. 2 is a top plan view thereof. Fig. 3 is an end ele-

vation. Fig. 4 is a similar view, looking toward the opposite end of the machine. Fig. 5 is a sectional view on the line 5—5 of Fig. 2. Fig. 6 is a sectional view on the line 6—6 of Fig. 2. Fig. 7 is a sectional view on the line 7—7 of Fig. 2. Fig. 8 is a perspective view of the tread plate finished.

Similar reference characters indicate corresponding parts throughout the several views in the drawings.

Referring to the drawings in detail, 10 designates the bed or table, and 11 the supporting legs, which constitute the frame of the machine. Rising from the bed or table 10 at opposite ends thereof are vertical end 70 walls 12, the same being reinforced and rendered rigid by means of upwardly bowed bridge bars 13 and 14 respectively, which are integral with the said walls. Secured to the under face of the bed or table 10 are 75 spaced parallel angle bars 15, the same being extended beyond one end of the frame and on them is mounted a split bearing 16 having journaled therein a driving shaft 17, the outer end of which carries a belt pulley 80 18 for connection with a motor or other driving power.

Formed in the end walls 12 are front and rear bearing guideways or recesses 19 and 20 respectively, while projected into the 85 front guideways 19 and mounted upon the bed or table 10 are split stationary bearings 21 in which are journaled the ends of a shaft 22, the same being also fitted in a medial stationary bearing 23 rising from the bed or 90 table 10, and this shaft 22 is fitted with a pair of corrugated rolls 24 which are spaced apart and are located on opposite sides of the medial bearings 23 for rotation between the same and the end walls 12 rising from 95 the bed or table 10 of the frame of the machine.

Fitted to one end of the shaft 22 is a gear 25, the same meshing with a pinion 26 fixed to the driving shaft 17 so that motion from 100 the latter will be imparted directly to the journal 22 for rotating the rolls 24 thereon.

Arranged above the rolls 24 is a pair of independent upper corrugated rolls 27 which have their inner journal ends 28 engaged in 105 fulcrum bearings 29 provided with semi-circular shaped grooves 30 receiving fulcrum ribs 31 correspondingly shaped thereto and formed on a bearing block 32 integral with and depending from the front reinforce- 110

ing bar 13 centrally thereof. The outer journal ends 33 of the upper rolls 27 are engaged in slideable bearings 34 which are formed with grooves 35 receiving fulcrum keys 36 in which are swiveled adjusting screws 37, the same being threaded in the end walls 12 so that by the adjustment of the said screws 37 the upper rolls 27 can be angularly adjusted relative to the lower rolls 24 whereby on the passing of a tread plate between the corrugated rolls the extent of the corrugations formed thereby within the said plate will be varied from one edge to the other of the plate, it being understood of course that the upper rolls 27 mesh with the lower rolls 24 at the outer end portions thereof so that on driving the lower rolls 24 the upper rolls will rotate simultaneously therewith. The fulcrum ribs 31 and the fulcrum keys 35 permit the rocking of the upper rolls 27 on adjusting the screws 37 for varying the angular pitch of the said upper rolls.

Formed above the base or table 10 of the frame of the machine centrally thereof are bearings 38 in which are journaled the trunnions 39 of an inverted U-shaped rocking beam or support 40 formed with end bearings 41 fitted within the rear guideways or recesses 20 in the end walls 12, the bearings 41 being provided with vertical slots 42 in which are engaged the journal ends 43 of upper and lower smoothing rolls 44 and 45 respectively, the journal ends 43 of the upper roll 44 being vertically adjustable in the slots 42 by means of slide blocks 46 in each of which is swiveled an adjusting screw 47 which is threaded in its respective bearing 41, while threaded in the end walls 12 are adjusting screws 48 which act upon the bearings 41 to swing the beam or support 40 and lock it in adjusted position so that the smoothing rolls 44 and 45 will be angularly disposed relative to the base or table 10 of the frame of the machine.

Formed on the bridge bar 14 and depending therefrom is a bearing 49 which is in alignment with the trunnion 39 of the rocking support 40, and in this bearing 49 is journaled a stud axle 50 of a beveled gear 51 which is neutral and meshes with similar beveled gears 52 mounted on the respective driven and counter shafts 53 and 54, the latter being journaled upon the rocking support 40, while the driven shaft 53 is journaled on the base or table 10 of the frame of the machine. The driven shaft 53 has fixed to its outer end a gear 55 meshing with a pinion 56 fixed to the driving shaft 17, while the counter shaft 54 has fixed to its outer end a pinion 57 meshing with a gear 58 fixed to the outer journal end 43 of the lower smoothing roller 45, the speed of rotation of the latter being slightly greater by reason of the gear connections therewith than the

lower corrugated rollers 24 during the operation of the machine so that after the plate 60 is corrugated and passes between the smoothing rolls 44 and 45 the same will be properly twisted for the shaping thereof when finished. These plates 60 are made in rights and lefts so that it is necessary to adjust the machine by the shifting of the rocking support 40, which properly positions the smoothing rollers whereby the plates 60 when passing through the machine will be properly shaped as a right or left plate, as the occasion requires.

By reason of the travel of the rolls 44 and 45 faster than the corrugated rolls 24 and 27 it enables the ironing or smoothing of the corrugations more readily, yet if desired the roll 44 may be fixed in the side walls 12 and the roll 45 capable of adjustment in a vertical direction, and following these rolls may be small rolls so placed as to start the edges of the plate one up and the other down and vice versa as regards "rights" and "lefts".

As shown in Fig. 1 of the drawings the upper rollers 27 are maintained at an angle to the rolls 24. These upper rollers 27 are maintained at an angle by downward pressure of blocks 34 against the ends of the shafts 33, the outermost edges of the rolls 27 being seated against the outermost edges of the rolls 24.

From the foregoing it is thought that the construction and manner of operation of the device will be clearly understood, and therefore a more extended explanation has been omitted.

What is claimed is:—

1. A machine of the class described comprising a base, vertical end walls rising from the base, upwardly bowed bridge bars connected to said walls, angle plates fixed to the under face of the base and disposed in parallel relation to each other, a split bearing mounted upon the said bars, a driving shaft journaled in the bearing, the said end walls being formed with front and rear guideways, medial bearings rising from the base, stationary bearings arranged in the front guideway, a shaft journaled in the said stationary bearings and also the medial bearings, corrugated rollers on the said shaft and disposed at opposite sides of the medial bearing, a pair of independent corrugated rollers arranged above the first-named rollers, fulcrum bearings arranged at the inner ends of the last-named rollers, slideable bearings arranged in the front guideways and working against the outer ends of the said pair of upper rollers, adjustable fulcrum keys arranged in the end walls and acting upon the slideable bearings for the angular adjustment of the upper pair of rollers relative to the first-named rollers, connections between the first-named rollers and the said

driving shaft, and upper and lower smoothing rollers having bearings arranged in the rearmost guideway.

2. A machine of the class described comprising a base, vertical end walls rising from the base, upwardly bowed bridge bars connected to said walls, angle plates fixed to the under face of the base and disposed in parallel relation to each other, a split bearing mounted upon the said bars, a driving shaft journaled in the bearing, the said end walls being formed with front and rear guideways, medial bearings rising from the base, stationary bearings arranged in the front guideway, a shaft journaled in the said stationary bearings and also the medial bearings, corrugated rollers on the said shaft and disposed at opposite sides of the medial bearing, a pair of independent corrugated rollers arranged above the first-named rollers, fulcrum bearings arranged at the inner ends of the last-named rollers, slideable bearings arranged in the front guideways and working against the outer ends of the said pair of upper rollers, adjustable fulcrum keys arranged in the end walls and acting upon the slideable bearings for the angular adjustment of the upper pair of rollers relative to the first-named rollers, connections between the first-named rollers and the said driving shaft, upper and lower smoothing rollers having bearings arranged in the rearmost guideway, and connections between certain of the smoothing rollers and the said driving shaft.

3. A machine of the class described comprising a base, vertical end walls rising from the base, upwardly bowed bridge bars

connected to said walls, angle plates fixed to the under face of the base and disposed in parallel relation to each other, a split bearing mounted upon the said bars, a driving shaft journaled in the bearing, the said end walls being formed with front and rear guideways, medial bearings rising from the base, stationary bearings arranged in the front guideway, a shaft journaled in the said stationary bearings and also the medial bearings, corrugated rollers on the said shaft and disposed at opposite sides of the medial bearing, a pair of independent corrugated rollers arranged above the first-named rollers, fulcrum bearings arranged at the inner ends of the last-named rollers, slideable bearings arranged in the front guideways and working against the outer ends of the said pair of upper rollers, adjustable fulcrum keys arranged in the end walls and acting upon the slideable bearings for the angular adjustment of the upper pair of rollers relative to the first-named rollers, connections between the first-named rollers and the said driving shaft, upper and lower smoothing rollers having bearings arranged in the rearmost guideway, connections between certain of the smoothing rollers and the said driving shaft, and means for angularly adjusting the smoothing rollers relative to the base.

In testimony whereof I affix my signature in presence of two witnesses.

GEORGE R. GIBSON.
